[57] CLAIM

The ornamental design for a corner connector for a modular storage container, as shown and described.

DESCRIPTION

FIG. 1 is a top, front, and left side perspective view of a corner connector for a modular storage container showing my new design;

FIG. 2 is a bottom plan view;

FIG. 3 is a top plan view;

FIG. 4 is a front elevational view;

FIG. 5 is a rear elevational view;

FIG. 6 is a right side elevational view; and,

FIG. 7 is a left side elevational view thereof.

FIG. 1

FIG. 2

FIG. 4

FIG. 3

FIG. 5

FIG. 6

FIG. 7
